COMPENSATING ATTACHMENT FOR PRESSURE CONTROLLERS

Harold L. Colby, Milton, Mass., assignor to Eldon MacLeod, Westwood, Mass., Frank A. Morrison, Newton, Mass., Cameron MacLeod, Berwyn, Pa., Leslie Soule, Dedham, Mass., and Sullivan A. Sargent, Jr., Needham, Mass., trustees, doing business as Mason Neillan-Regulator Company, Boston, Mass.

Application May 28, 1932, Serial No. 614,233

4 Claims. (Cl. 50—10)

This invention relates to control mechanism and particularly to control mechanism having a compensating action and utilizing an independent fluid pressure pilot control.

5 The invention herein constitutes an improvement on the type of control mechanism disclosed in Annin Patent No. 1,991,309, granted February 12, 1935, and lies in providing a compensating attachment therefor. It has been found by experience that the Pressure controller embodied in 10 Annin Patent No. 1,991,309 is not suitable for all types of installation without mechanical adjustment. In some industrial plants in which the device is installed, for instance, the motor valve 15 may be placed too far away from the pilot control mechanism, or the motor valve may be too large for the fluid capacity, or the piping arrangement of the compressed air to the motor valve may be such as to interpose a resistance to the 20 air flow, thereby causing a time lag which the instrument cannot automatically handle. As a consequence in these installations, fluctuations and a hunting action in the control will occur unless extensive adjustment is made.

25 I have been able to successfully overcome these difficulties by providing a second Bourdon tube attached to the cleaver arm closing and opening the exhaust port of the pilot control which is actuated by the pressure from the central diaphragm chamber as the exhaust port is closed. The action of this second Bourdon tube is opposite in direction to that of the first Bourdon tube which is actuated by the pressure of the medium being controlled. Thus, as Annin's exhaust port 30 is closed and pressure in the central diaphragm chamber 15 is built up, this accumulating pressure operates through my second Bourdon tube to open the port partially. Time lag before the motor valve is operated and the usual over-travel 35 or hunting action is prevented, because the original impulse of the pilot control mechanism is offset or compensated before such over-travel can occur. This compensating action produces a stabilizing condition and renders this type of control suitable for all types of installation without mechanical adjustment.

40 Other objects of this invention will appear in the following description and appended claims reference being had to the accompanying drawing formed a part of this specification.

45 The drawing is a front elevation of my control mechanism with the compensating attachment, part of the control mechanism being broken away to show the interior thereof.

50 Before explaining in detail the present inven-

tion, it is to be understood that the invention is not limited in its application to the details of construction and arrangement of parts illustrated in the accompanying drawing, since the invention is capable of other embodiments and of being practiced or carried out in various ways. Also 5 it is to be understood that the phraseology or terminology employed herein is for the purpose of description and not of limitation, and it is not intended to limit the invention beyond the terms 10 of the several claims hereto appended as considered in view of the prior art and the requirements thereof.

The numeral 1 designates a feed line controlled by a diaphragm motor valve 2, and this motor 15 valve is operable by fluid pressure through a pipe 3. The pilot controller proper comprises a preferably cylindrical casing divided into five sections 4, 5, 6, 7, 8, separated by a series of diaphragms 9, 10, 11, 12. In this manner, the casing 20 is divided into five chambers 13, 14, 15, 16, and 17.

Fluid pressure from an independent pressure system is admitted to the casing through a pipe 18, into the chamber 13 controlled by a reducing or supply valve 19 of the diaphragm 9. The 25 chamber 13 communicates with the chamber 17 in any suitable manner, as by a pipe or duct 20. The diaphragm 12 supports a waste valve 21, controlling an exhaust 22. The aforesaid pipe 3 30 communicates with the chambers 13 and 17. Normally, when the diaphragms are at rest, the waste valve 19 is closed and the supply valve 21 open, cutting off the supply of fluid pressure to the diaphragm motor valve 2 and wasting the pressure in the pipe 3 through the discharge duct 35 22.

From the pipe 18 extends a pipe 23, which communicates through a duct 41, to the center chamber 15. The lower portion of the duct 41 terminates in an orifice 25, covered by a dial 26, which 40 in turn is provided with a series of ports 27, for registration with the orifice of this pipe. On a pivot 28 is mounted a lever 29, terminating at one end in a plate 30, and this plate rests against the surface of the dial 26. The opposite end of 45 the lever 29 is connected by a link 31, to which is attached at its bottom end, a horizontal lever 70 pivotally suspended at its middle from the link 31. From one end of lever 70 is suspended the link 31a connected to the helical or Bourdon tube 50 32. From the other end of the lever is suspended a corresponding link 71 connecting with the helical or Bourdon tube 12. The Bourdon tube 12 is arranged so as to move oppositely to Bourdon tube 32, and as the first Bourdon tube 32

acts to move the cleaver arm 29 through links 31a, lever 70 and link 31 in one direction, the second Bourdon tube 72 acts through the same links and lever to move the cleaver arm 29 in the opposite direction.

Bourdon tube 72 is actuated by the air pressure leading to it through pipe 73 from duct 41. By an alternative arrangement (not shown) air may be fed to the Bourdon tube 72 from the same system but directly from the central diaphragm chamber 15.

The operation of the device will be obvious from the specification and drawings of Annin Patent No. 1,991,309, to which reference is hereby made. Assuming that the mechanism illustrated herein is set for maintaining an exact back pressure in the main feed line 1, the diaphragms 9, 10, 11 and 12 are at rest, and diaphragm motor valve 2 is held closed by its spring 34. If back pressure builds up in the main feed line 1 it passes through pipe 33 to the helical tube 32, tending to unwind the latter and thereby to turn lever 29 as to gradually reduce the size of the exhaust orifice 25. On the closing of exhaust orifice 25 pressure in diaphragm chamber 15 builds up, forcing waste valve 21 and port 22 closed and supply valve 19 open, allowing pressure from pipe 18 to enter directly into chamber 13, flow through pipes 20 and 3 to diaphragm motor valve 2 which opens against the tension of its spring 34 to relieve the back pressure. Then compensation occurs. As pressure in feed line 1 actuates Bourdon tube 32 to close the exhaust port 27 by means of the cleaver arm 29, pressure in duct 41 is built up and flows to the second Bourdon tube 72 which, acting in an opposite direction, tends to move cleaver arm 29 to open slightly the exhaust port 27. By means of this compensating attachment, the adjustable Rotaport feature, comprising dial 26 and ports 27 varying in size can be eliminated, and one exhaust port substituted, if desired. It will also be understood that where "Bourdon tube" is mentioned herein in the specification, a helical tube or other pressure responsive element can be substituted.

Thus it will be seen that the control mechanism disclosed in Annin Patent No. 1,991,309 is provided with a compensating action supplied by pressure from the pilot control mechanism. In this way any time lag before the motor valve is operated and the usual over-travel or hunting action, is prevented, because the original impulse of the pilot control system operating the motor valve is offset or compensated before such over-travel can occur.

I claim:

1. Control mechanism of the class described, a diaphragm motor valve governing the supply of a medium under control, an air pressure system for operating said motor valve ordinarily exhausting to the atmosphere, an exhaust port through which said pressure system ordinarily exhausts to the atmosphere, a closure arm for closing said exhaust port, a tube responsive to the pressure of the medium under control for actuating said closure arm, pilot valve means including independent supply and waste valves governing the supply and waste of pressure in said system, and diaphragm mechanism acted on by said pressure and actuating said supply and waste valves to divert said pressure to operate said motor valve on the closing of said exhaust port by the closure arm, a second tube responsive to the pressure in said pressure system and acting in a

direction opposite to the first tube for counteracting the movement of said closure arm as actuated by the first tube.

2. Control mechanism of the class described, a diaphragm motor valve governing the supply of a medium under control, an air pressure system for operating said motor valve ordinarily exhausting to the atmosphere, an exhaust port through which said pressure system ordinarily exhausts to the atmosphere, a closure arm for closing said exhaust port, a tube responsive to the pressure of the medium under control for actuating said closure arm, pilot valve mechanism including a pair of diaphragms dividing said mechanism into two outer chambers and an inner chamber, a supply valve and a waste valve in said outer chambers governing the supply and waste of pressure in said system, said pressure expanding said inner chamber and actuating said supply and waste valves to divert said pressure to the motor valve for operating the same on the closing of said exhaust port by the closure arm, a second tube responsive to the pressure in said pressure system and acting in a direction opposite to the first tube for counteracting the movement of said closure arm as actuated by the first tube.

3. Control mechanism of the class described, a control valve governing the supply of a medium under control, an independent pressure system for operating said control valve ordinarily exhausted to the atmosphere, an exhaust valve governing the exhaust from said system, means responsive to a variable of the medium under control for actuating said exhaust valve, pilot valve mechanism including a pair of diaphragms dividing said mechanism into two outer chambers and an inner chamber, a supply valve and a waste valve in said outer chambers governing the supply and waste of pressure in said system, said pressure expanding said inner chamber and actuating said supply and waste valves to divert said pressure to the control valve for operating the same on the closing of said exhaust valve, and means in said pressure system for counteracting the movement of said exhaust valve as actuated by the variable of the medium under control.

4. Control mechanism of the class described, a diaphragm motor valve governing the supply of a medium under control, an air pressure system for operating said motor valve ordinarily exhausting to the atmosphere, an exhaust port through which said pressure system ordinarily exhausts to the atmosphere, means for adjusting the size of said exhaust port, a closure arm for closing said exhaust port pivoted intermediate its ends, a Bourdon tube responsive to the pressure of the medium under control for actuating said closure arm, pilot valve means governing the supply and waste of pressure in said system including diaphragm mechanism acted on by said pressure and actuating said pilot valve to divert the pressure to the motor valve to operate the same on the closing of said exhaust port by said closure arm, a second Bourdon tube responsive to the pressure in said pressure system and acting in a direction opposite to the first tube for counteracting the movement of said closure arm as actuated by the first tube, including a second lever connected at its ends to said Bourdon tubes and a link connected at one end to said closure arm and at its other end pivotally supporting said second lever intermediate its ends.
